UNITED STATES PATENT OFFICE.

BEVERLY DOUGLAS, OF BALTIMORE, MARYLAND.

DEVICE FOR SUPPLYING HEATED VAPOR TO INTERNAL-COMBUSTION ENGINES.

1,373,603.

Specification of Letters Patent.

Patented Apr. 5, 1921.

Application filed December 23, 1919. Serial No. 346,919.

To all whom it may concern:

Be it known that I, BEVERLY DOUGLAS, a citizen of the United States, and resident of Baltimore, in the State of Maryland, have 5 invented certain new and useful Improvements in Devices for Supplying Heated Vapor to Internal-Combustion Engines; and I do hereby declare the following to be a full, clear, and exact description of the same, 10 reference being had to the accompanying drawings, forming part of this specification.

This invention relates to an improved means for admitting and controlling the admission of hot vapor to the fuel charge of 15 internal combustion engines, the objects of the invention being to provide a practical form of mechanism which may be readily applied to well known types of popular motor 20 cars. The invention embodies means whereby the driver may control and regulate the action and whereby the operation and rate at which hot vapor is admitted may be observed at any and all times. The indicator 25 for observation purposes is made an attractive feature calculated to enhance the pleasure of driving and enabling the driver to have the satisfaction of knowing that the apparatus is functioning correctly and, 30 therefore, that the motor is operating at maximum efficiency for the existing conditions.

In the accompanying drawings,—

Figure 1 is a side elevation partly in section and partly diagrammatic of a motor car engine plant and steering wheel and post with the invention adapted thereto.

Fig. 2 is an elevation looking at the opposite side of the engine plant from that 40 shown in Fig. 1.

Fig. 3 is a detail sectional elevation of the carbureter air intake showing the arrangement for discharging hot vapor into the same.

Fig. 4 is a section on the line 4—4, Fig. 3.

Fig. 5 is a sectional elevation of the intake and indicator mechanism of the hot vapor system.

Figs. 6 and 7 are sections respectively on 50 the lines 6—6 and 7—7 of Fig. 5.

The engine plant adopted for illustrating the invention is one of the popular and extensively used types which, because of its well known construction, will need no description further than to say that A are the 55 cylinders, B the crank case, C the transmis-

sion case, and D the radiator and water reservoir communicating through pipes d, d', with the water jacket of the cylinder block.

In Fig. 2 the usual exhaust manifold E, 60 intake manifold F and carbureter G are shown, and these parts with the parts heretofore mentioned are intended to be utilized without change or alteration in adapting the present invention thereto.

In carrying the invention into practice, the hot vapor in the radiator or tank heated from the engine is preferably utilized, and for this purpose a supply pipe I is extended down through the overflow pipe K, and at 70 the lower end where it emerges from said overflow pipe it is jointed at I' to a section of the pipe I² extending to the air intake pipe of the carbureter. At some point in the vapor supply pipe I', I², it is preferably provided with a priming cock I³, although this is optional.

In the usual equipment of motor car plants, the overflow pipe K may be of a 80 diameter which is smaller than would accommodate the proper size vapor supply pipe, and where this is the case, it is preferred to provide an overflow pipe of enlarged diameter and this overflow pipe may be conveniently installed by insertion 85 through the usual filling cap opening L and held in place by clamping nuts and washers k which form a water-tight connection so as to prevent the leakage of water from the radiator. As a preferred equipment, the 90 vapor supply pipe is itself covered by a heat insulating cover indicated in dotted lines.

To insure the proper admission and admixture of the hot vapor and its control, the usual or a specially provided air supply 95 pipe M leading to the carbureter and preferably having its intake end in proximity to the exhaust manifold is provided with an internal valve located above or on the outer side of the discharge nozzle I⁴ of the vapor 100 supply pipe. This valve is controlled manually from the driver's seat and by opening it more or less the degree of vacuum created in the air intake pipe may be regulated and the relative proportion of hot vapor from the water supply tank or radiator 105 will be correspondingly controlled, inasmuch as its flow will depend upon the suction to which its discharge end is subjected.

The preferred and most efficient arrangement is shown in detail in Fig. 3 of the accompanying drawings, wherein it will be

seen that the air supply pipe M corresponds in form and construction to the usual air supply pipe, and within it I locate the means for augmenting the mixing of the hot vapor and air, preferably formed by a cylindrical body N having a tapered lower end N' from the apex of which the nozzle I^* of the vapor supply pipe projects, the said nozzle being preferably curved when 5 the device is located at the elbow of the air pipe as shown in the said figure of the drawings. The conical or tapered portion of the cylindrical body N is also provided with a series of air admission openings N^2 through 10 which the air is forced to travel and whereby the air currents will be broken up to insure a thorough mixing of the vapor with the air before the air reaches the carbureter and before the fuel vapor combines there- 15 with, it being one of the features of the present invention that the hot vapor and air are combined prior to the combination of the carbureter fuel with the air. The cylindrical body N , preferably cone-shaped, 20 at its upper end is provided with a series of apertures n' , and is adapted to support and to fit snugly against a rotary valve O , also cone-shaped, having a corresponding series 25 of apertures o therein. When the apertures 30 in the head of the mixer and valve are in registry there is in operation no increased obstruction to the flow of air through the air intake pipe. This however, may be regulated by opening or closing the valve through the 35 medium of a projecting arm O' and a flexible connection O^2 extending back to a convenient handle O^3 on the steering wheel post P , so as to give any desired resistance and consequently any desired vacuum in the 40 air intake pipe, with the result that accurate control of the relative proportions of air and hot vapor which will be admitted to the carbureter is possible. As a constructive detail, the pipe I^2 , preferably extends axially through the cylindrical body N and 45 serves as the pivot for the valve O . To hold this valve down to its seat, a spring o' , is located above the same and between it and a collar o^2 on the pipe I^2 .
50 Air is admitted to the top of the radiator or supply chamber through a device preferably attached to and forming a part of the filler opening cap R , and this device embodies in its construction a visible indicator 55 showing the relative quantity of air being admitted and consequently the quantity of hot vapor laden air which is passing from the top of the radiator to the carbureter. The preferred arrangement is shown in its 60 general form in Fig. 1 and in detail in Figs. 5, 6 and 7. It embodies a downwardly projecting inlet pipe R' secured in an aperture in the filler cap R and having at its lower end a ball or other suitable valve R^2 adapted 65 to close for preventing any outward flow of

water or air from the top of the radiator; but to permit air to move readily into the same. This pipe R' is preferably secured in place by a lock nut r , and at its outer end screws into a fitting R^3 having a three-way 70 duct therein. In one of the branches there is an inwardly opening and outwardly closing adjustable valve S . In another of its branches there is connected an indicator device embodying a vertically arranged gage 75 glass fitting T , from the lower end of which an upwardly extending branch intake pipe T' projects to a point within a shield t' , whereby access of dust, etc., is prevented. The upper end of the gage glass fitting T 80 communicates with a horizontal pipe T^2 in communication with the aforesaid branch of the fitting R^3 , and in operation the gage glass fitting and branch intake pipe T' are adapted to be partly filled with a non-volatile transparent oil through which air drawn in through the small perforations t^2 in the end of the branch pipe T' will bubble and may be readily observed from the driver's seat. In order to make this portion of the 85 apparatus more effective, it is preferred to locate around the gage glass on the side opposite the driver's seat a curved and highly polished reflector V , inasmuch as practice has demonstrated that even at 90 night, with such a reflector in position the bubbles of air passing through the clear oil are readily observable, and should, for any reason, there be a stoppage or cessation 95 of the action of the device, the quiescent condition of the oil will attract attention. By providing an adjustable valve S , the proportion of air which passes in through the branch pipe T' may be accurately regulated, so that a wide variation in the agitation of the clear oil will be produced by 100 opening more or less the regulating and controlling valve O . The driver from his seat will know instantly and continuously by observation whether or not the device is 105 functioning correctly and in the desired way for the visible indicator is made dependent upon the conditions existing in the air intake pipe at a point in advance of the carbureter.

As a matter of convenience in construction, the guard t' for protecting the end of the branch inlet piping T' is formed of a piece of sheet metal which is bent around the pipe T^2 and extended down on opposite sides of the flattened end of the branch pipe T' , thus leaving the small inlet openings t^2 free from obstruction, and at the same time protecting them against the entry 110 of dirt, or the branch pipe T' against injury 115 or lateral deflection.

While some air may enter the upper portion of the radiator or supply tank through the overflow pipe, yet the length of this pipe and the small area around the vapor 120 125 130

pipe seems to obstruct such flow to a degree where the volume of air so entering is of no material consequence, a practical device in a long continued use having shown 5 that the indicator mechanism operates with certainty and efficiency under the exact conditions illustrated and described, but at the same time it should be borne in mind that the entry of air through this source 10 should be restricted to a point where the ends described will be attained, although it is not believed that any valve mechanism is essential to attain the result.

With the device of the present invention 15 it is found that there is a material saving in the fuel consumption and an increased power from the engine, a definitely cooler engine, and relative freedom from carbon deposit. In fact, the operation of the device 20 seems to produce constant and stable conditions closely approximating the conditions which every driver has observed to exist during damp weather or in the damp cool of the evenings, when aqueous vapor 25 is present in large percentage in the air fed to the carbureter. Furthermore, the stream of warm vapor passing through the carbureter keeps the carbureter at a constant temperature winter and summer. The constant 30 agitation and bubbling of the clear oil in the indicator not only serves a useful function in that the driver may by observing the violence of the agitation determine the way in which the device is functioning, but it 35 adds an attractive feature to the motor vehicle itself in the nature of an ornament which is in constant motion while the engine is running.

Lastly, if at any time the engine becomes 40 overheated to the point of causing the water in the cooling system to boil, the negative vapor pressure in the radiator becomes positive from steam formation, and the bubbling in the gage will immediately 45 cease. The indicator, therefore, also serves as an accurate and reliable indicator of overheating.

With the arrangement described, it is found that when desirable to reinforce or 50 possibly entirely supplant the fuel supplied through the carbureter, it may be accomplished by having the radiator or tank supplied with volatile combustible such, for example, as kerosene, alcohol, or other fuel. 55 The apparatus may be employed without change where the radiator constitutes the vapor supply chamber, but if a chamber other than the radiator be employed, the pipe connections will lead to it in the same 60 manner as illustrated in connection with the radiator.

What is claimed is:

1. In a device for supplying hot vapor to 65 internal combustion engines, the combination with a carbureter, an air intake pipe to

the carbureter, a vapor supply pipe opening into said air intake pipe to the carbureter, and a valve in said air intake pipe on the outer side of the vapor supply pipe opening.

2. In a device for supplying hot vapor to 70 internal combustion engines, the combination with a carbureter intake air supply pipe, a means mounted in said air supply pipe for augmenting the commingling of the air and vapor, a vapor supply pipe for 75 supplying vapor to the air at said mixer, and an air control valve in said supply pipe for regulating the quantity of air passing to the commingling augmenting means.

3. In a device for supplying hot vapor to 80 internal combustion engines, the combination with a vapor supply chamber an air intake pipe for supplying air to the carbureter, of a valve located in said intake pipe for controlling the flow of air therethrough, 85 a vapor supply pipe opening into said air supply pipe on the inner side of the valve, manually operable means for controlling the opening and closing of the valve, whereby the relative proportions of air and hot 90 vapor may be regulated, and means for visually indicating the volume of air supplied to the vapor supply chamber.

4. In a device for supplying hot vapor to 95 internal combustion engines, the combination with an air intake pipe for supplying air to the carbureter for creating a fuel mixture, of a mixing augmenting means mounted in said air supply pipe and having an apertured and tapered inner end, a 100 vapor supply pipe opening in proximity to the apex of the tapered end of the mixing augmenting means, and a manually controlled air regulating valve located in said air intake pipe on the outer side of the mixing 105 augmenting means and vapor supply pipe opening.

5. In a device for supplying hot vapor to 110 internal combustion engines, the combination with an air intake pipe for supplying air to a carbureter to form a fuel mixture, a mixing augmenting means mounted in said air supply pipe, a vapor supply pipe having its inlet nozzle located in proximity to the inner part of the mixing augmenting 115 means, a manually controlled valve embodying an apertured member mounted at the outer end of the mixing augmenting means, and a spring for permanently holding said valve to its seat.

6. The combination with a motor vehicle 120 power plant embodying an engine, radiator and water circulating system including the radiator, of a vapor supply pipe leading from the top of the radiator to the engine 125 intake pipe, and an air inlet mechanism associated with the top of the radiator and embodying an intake pipe having a non-return valve therein and a gage glass visible from the driver's seat, with means whereby 130

incoming air is directed to the bottom of said gage glass, and a non-volatile oil located in said gage glass whereby it will be agitated by the incoming air and the entrance of the latter may be observed by the driver of the vehicle.

7. The combination with a motor vehicle power plant embodying an engine, radiator and circulating water system, of a vapor supply pipe leading from the top of the radiator to the engine intake, a filler opening, a cap for said opening, and an air intake associated with said cap and embodying a supply duct leading through the cap, a gage glass in communication with said supply duct at its upper end, means for directing incoming air to the bottom of the gage glass, and a clear oil held in said gage glass and through which the incoming air is caused to bubble.

8. In a device such as described, the combination with a filler cap for a motor vehicle radiator, of an air intake mechanism embodying an inlet duct passing through said filler cap, a gage glass in communication at its upper end with said inlet pipe,

an upwardly directed air inlet pipe communicating with the lower end of the gage glass, a reflector partially surrounding said gage glass, and a nonvolatile oil located in the gage glass whereby incoming air will be caused to bubble through the oil in passing to the radiator, a non-return valve in the inlet pipe, and means for conducting heated vapor from the top of the radiator to the intake pipe of the engine.

9. In a device such as described, the combination with a filler opening cap of a motor vehicle radiator from which radiator hot vapor is supplied to the engine, of an intake pipe passing through the radiator cap, a non-return valve in said pipe, a valved inlet to the pipe, a branch inlet to the pipe embodying a gage glass communicating at its upper end with the inlet pipe, an upwardly directed branch inlet pipe having its inlet openings above the level of the gage glass, a shield protecting the inlet openings of the branch pipe, and a transparent oil located in the gage glass and upwardly directed branch inlet pipe.

BEVERLY DOUGLAS.
